[57] CLAIM

The ornamental design for golf putter head, as shown and described.

DESCRIPTION

FIG. 1 is a perspective view of the golf putter head showing my new design;

FIG. 2 is a right side view thereof;

FIG. 3 is a left side view thereof;

FIG. 4 is a bottom view thereof;

FIG. 5 is a front inverted view thereof;

FIG. 6 is a top plan view thereof; and,

FIG. 7 is a back inverted view thereof.

The broken line showing of a shaft segment is for illustrative purposes only.
